FORK OR SIMILAR ARTICLE OF FLATWARE

Siro R. Toffolon, Meriden, Conn., assignor to The International Silver Company, Meriden, Conn., a corporation of Connecticut

Filed Jan. 4, 1966, Ser. No. 443

Term of patent 14 years

(Cl. D54—12)

FIG. 1 is a front elevational view of a fork showing my new design;

FIG. 2 is a rear elevational view;

FIG. 3 is a side elevational view;

FIG. 4 is a cross-sectional view taken on line 4—4 of FIG. 1;

FIG. 5 is a cross-sectional view taken on line 5—5 of FIG. 1; and

FIG. 6 is a cross-sectional view taken on line 6—6 of FIG. 1.

The stippling on the face of the raised left side section of the front of the handle, as observed in FIG. 1, represents a dulling surface treatment of the satin finish type obtainable by burnishing as contrasted with relatively high surface polishing of the right side section thereof.

The design is intended for use on sets comprising forks, spoons, knives and similar articles of flatware.

I claim:

The ornamental design for a fork or similar article of flatware, substantially as shown and described.
